UNITED STATES PATENT OFFICE.

KNUT G. THIMAN, OF NEW YORK, N. Y.

PLUG-COCK.

1,283,356.

Specification of Letters Patent. Patented Oct. 29, 1918.

Application filed May 17, 1916. Serial No. 98,091.

To all whom it may concern:

Be it known that I, KNUT G. THIMAN, a citizen of Sweden, and resident of the borough of Manhattan, in the county of New York and State of New York, have invented certain new and useful Improvements in Plug-Cocks, of which the following is a specification.

This invention relates, in general, to valves 10 of the rotatable variety, wherein a turn-plug is made to control a passage through a casing, but in more restricted sense it is especially applicable to gas-cocks, such as are employed in conjunction with illuminating fixtures.

One of the objects of the invention is to produce an improved device of the nature set forth, capable of being quickly regulated so that the gas or other fluid flowing there- 20 through may be had either in a full stream, or reduced to the tiniest jet that can feed a flame, or entirely cut off, simply by turning the plug in one of three readily determined positions.

25 A further object is the production of a device of the character described including a peculiarly designed means of manipulation for the plug member thereof, which shall be so constructed and arranged as to 30 enable the operator through groping in darkness, to ascertain at once and unerringly the position in which it stands, by the mere sense of touch.

Another object is to provide a device of 35 the species mentioned which shall favorably compare with the common, inexpensive form of gas cock now on the market, being composed of as few, simple and durable parts, and thereby rendered amenable to low cost 40 of manufacture, besides admitting of convenient manipulation by any person of average intellect.

Other objects and advantages of the invention will become apparent as the specification proceeds.

With the aforesaid objects in view, the invention consists of the improvements, novel construction, arrangements and combinations of parts hereinafter described, defined in the subjoined claims and illustrated in their preferred embodiments by the annexed drawings, wherein like elements are designated by the same reference characters throughout.

In the said drawings:

Figure 1 is a central longitudinal section of the device, the section running along the line 1—1 of Fig. 4, looking in the direction indicated by the arrows in the latter named figure, and the rotatable member being 55 changed in position;

Figs. 2 and 3 are views similar to the preceding with the said member differently positioned;

Fig. 4 is a longitudinal section on the line 65 4—4 of Fig. 3, looking toward the left; and

Fig. 5 is a transverse section on the line 5—5 of Fig. 1, looking in an upward direction.

In these views the numeral 11 denotes the 70 body or casing of a gas-cock constructed in accordance with the present invention, which in its preferred form comprises a central laterally protuberant part 12, contracted neck-portions 13, 14 integral therewith, and terminals 15, 16 also swelled-out, and reinforced by circumferential beads 17, 18, respectively. The terminals are provided with recesses 19, 20 one in each, which are internally threaded and constitute sockets for the 80 reception of gas conduit pipes (not shown) wherewith the device is usually connected up.

With the exception of the laterally-pro- 85 tuberous part 12 aforesaid, more particu- 90 larly referred to hereinafter, the above 95 enumerated elements combine features that are found in the ordinary types of gas-cocks or faucets, all of which readily assimilate with the invention. But it is un- 100 derstood that other features of construction may well be adopted instead. Thus, al- though the present exemplification of the invention indicates that the device has double pipe sockets, no limitation in this sense is intended, as the sockets, or either of them, may be replaced by externally threaded ends, or the device may have sockets or terminals respectively tapered interiorly and exteriorly, or any interchange or interpolation between the connections used in gas-fixtures generally, such as any of the cocks sold by the trade, the various species of which are defined by the terms "straight", "elbow", "bracket", "hose", "pendant", "swing", "revolving", "pillar," etc.

The before mentioned central part 12 has a bore 25, transverse to the longitudinal di-

mension of the body or casing 11. The said bore is tapered, that is, made conical to provide a seat for a correspondingly-shaped plug member, 26, fitted therein, so as to afford a fluid-tight connection. Alined ports 27, 28 of smaller cross-sectional area than the bore, intersect the latter at right angles to its transverse plane, but are eccentric thereto or offset toward one side of the axial line passing centrally lengthwise through the casing 11 and the plug member 26. The outer ends of these ports communicate with the previously mentioned recesses 19, 20, at the bottom of each, respectively. As the 10 two ports are eccentrically disposed on one side of the casing 11, the neck portions 13, 14 thereof are enlarged in the same direction in order to strengthen them, thereby giving each neck an elliptical shape, as at 15 21, 22.

A passage 29 is provided in the plug 26 at the same level as the said alined ports 27, 28, so as to communicate therewith, within the bore 25. As will be seen in the accompanying drawing, the said passage 29 consists of a channel of compound formation, comprising a main portion (29) of segmental shape, and a minor, accessory part including a groove 30, formed substantially 25 like a crescent-lune, commencing near one end of the said segmental passage and thence gradually becoming shallower or narrower as it winds around the plug member, until it entirely disappears at the surface of the latter. Preferably, the arrangement is such 30 that the point at which the said groove vanishes lies diametrically opposite the other end of the segmental channel 29.

In the position occupied by the plug member relatively to the casing in Fig. 1, the communication between the ports 27 and 28 is interrupted, to the extent of being 40 completely cut off. The change of position represented in Fig. 2, on the contrary, places the several straight-line passages through the valve casing and the plug in full register one with another. The valve is then completely open, so that a gas-burner, for instance, receiving its supply therethrough, 45 will feed a flame to the fullest extent. Fig. 3 illustrates the plug member 26 in a position diametrically opposite to that shown in Fig. 1, whereby the flow of gas is diminished and allowed to reach the jet in the 50 minimum quantity compatible with the feeding of the flame, to wit, without subjecting it to the danger of becoming extinguished. In the last named position of the 55 plug member, the reduced end of the groove 30 is directly in communication with the port 27 and permits only a tiny stream of gas to pass through, just enough to keep the flame alive or burning.

At the larger end of the conical plug 26 is 60 formed a handle portion or finger grip 31.

One edge of the latter may be obtusely beveled as at 32, to differentiate the shape thereof from that of the opposite edge 33, which may remain slightly rounded as customarily made. The beveled edge of the 70 finger grip is placed on the same side of the plug as the groove 30 therein. By virtue of this arrangement, a person is able to tell even in the dark, what is the position of the plug inside the casing at any given time 75 simply by passing his or her finger over the edges of the grip and noting if its bevel lies next to the laterally protuberant portion 12 of the casing 11, or is located adjacent to the approximately straight face of the cas- 80 ing directly opposite, or else occupies some intermediate position. This is of great importance in the case of a gas leak, or free escape of unburning gas for then the person investigating the cause thereof has a ready 85 means of ascertaining whether it is due to the valve being open in any way, or to a faulty fixture, and doing so without the use of an artificial light, which, as is well known, might produce a dangerous explo- 90 sion.

Figs. 1, 2 and 3 respectively illustrate three well defined positions of the plug member within its casing determining each by the particular location of the crescent lune before described. In the first, the reduced portion of the crescent-lune or groove 30, is on the laterally protuberant side of the casing, to wit, the left side in the present exemplification of the invention. In the 100 second, the groove lies across the interior of the casing. In the third, it has passed over to the right of the casing on the side remote from the lateral-protuberance 12, and pointed in a reverse direction. The several 105 positions here outlined respectively denote whether the passageway through the plug member is closed, or fully open, or restricted to the minimum without interrupting the flow therethrough. It will be recognized that no adjustment for intermediate 110 positions is necessary. This not only is conducive to safety, but also effects a saving of gas in practice, because it enables the user on leaving an apartment, readily to adjust 115 the burner to the lowest supply permissible, without trying to bring the flame gradually to the desired reduction in size.

Incidentally, it may be remarked that a gas-cock of this description is especially 120 suitable for bath and bed rooms, halls and cellars and in fact for all places that are not constantly inhabited. Obviously a graduated adjustment may also be had with a device constructed according to the principle 125 herein set forth, by turning its plug in different arcs or amounts, away from the right hand position exemplified in Fig. 3 of the annexed drawing, the peculiar configuration of the crescent-lune groove 30 permitting 130

fine regulation of the passage through the casing with a comparatively wide angular or arcuate movement of the finger grip 31 and the plug member 26 connected therewith.

To prevent over travel of the said member 26 from or beyond either of its extreme stations, respectively illustrated in Figs. 1 and 3, the common expedient of a pin 34 10 driven into one side of the plug and adapted to come into contact alternately with shoulders 35 and 36 formed on the casing 11, may be employed. The means for holding the plug from endwise movement in its seat 25 15 is shown as consisting of the prevalent type of washer and screw 37 and 38 respectively, which co-act with a neck 39, formed at the outer end of the said plug.

Although certain mechanical details of 20 known construction have been applied to the invention herein disclosed, it is evidently susceptible of other embodiments with substitutes of different structure, whether or not equivalent to the same. Furthermore, 25 it will be noted that the contour of various parts may vary to a considerable extent without affecting in the least the operativeness of the parts. Thus, for example, the finger grip 31 has been shown as formed 30 with the larger end of the conical plug member. But, it is readily comprehended that the grip can be as effectively located at the other extremity of the plug, or that a separate key or handle could be employed 35 for the manipulation of the device.

Having described my invention what I desire to secure by Letters Patent and claim is:—

1. A device of the character set forth, comprising a casing with a transverse bore and ports placed in alinement at one side of the latter, in combination with a plug rotatably seated in said bore and having a channel formed of a segmental passage and a crescent-lune groove either of which is adapted to register with both of said alined ports, alternately.

2. A device of the character set forth, comprising a casing provided with a transverse

bore and alined ports leading respectively 50 into and out of the same across one side thereof, in combination with a plug having one side adapted to interrupt the flow from one of said ports and the other side provided with a compound channel having outlets of 55 different sizes at opposite ends arranged to communicate with both ports in succession.

3. A device of the character set forth, comprising a casing formed with a substantially central bore extending transversely 60 thereof and eccentrically located ports in alinement at one side of the bore, combined with a plug in the latter having a laterally disposed channel of compound formation including a segmental passage and a crescent- 65 lune groove adapted alternately to be brought into register with both said ports.

4. A device of the character set forth, comprising a casing having a transverse bore and alined ports arranged to communicate 70 therewith at one side only, a rotatable plug member in said bore formed with a channel having terminals of different capacity either of which is adapted to register alternately with both of said ports, and external 75 means on said plug capable of indicating its position within the bore.

5. A device of the character set forth, comprising a casing provided with a transverse bore, alined ports on one side thereof, and 80 an external protuberance, in combination with a plug member rotatably seated in said bore and having a channel adapted to register with the latter, including a crescent-lune groove arranged to assume different 85 positions consecutively with relation to said protuberance and both ports, and means exterior to said member turning therewith coincidently with said groove so as to indicate its location relatively to said protuber- 90 ance.

Signed at the borough of Manhattan, in the county of New York and State of New York, this 8th day of May, A. D. 1916.
